UNITED STATES PATENT OFFICE.

ARTHUR W. CLAUDER, OF BRIDGEPORT, CONNECTICUT, ASSIGNOR TO GENERAL ELECTRIC COMPANY, A CORPORATION OF NEW YORK.

SNAP SWITCH.

Application filed August 19, 1920. Serial No. 404,629.

To all whom it may concern:

Be it known that ARTHUR W. CLAUDER, a citizen of the United States, residing at 26 Pacific St., Bridgeport, in the county of 5 Fairfield and State of Connecticut, has invented certain new and useful Improvements in Snap Switches, of which the following is a specification.

This invention relates to a snap switch of 10 novel construction, comprising few and simple parts which may be readily assembled and which is not liable to get out of order. It provides a construction wherein the operative members for the most part may be 15 stamped from sheet material and assembled without further manufacturing operations, the parts being held in relative position by a spring which furnishes the impelling force for closing and opening the circuit. The 20 switch by reason of its simple and compact construction is especially adapted for lamp sockets.

For a more complete understanding of the 25 invention together with other objects and advantages details and combination of parts reference may be had to the accompanying drawings in which—

Fig. 1 is an end view of the switch applied 30 to a lamp socket, the outer casing being removed,

Fig. 2 is a longitudinal or axial section thereof,

Fig. 3 is a perspective of the switch blade and actuating mechanism,

Figs. 4 and 5 are side elevations of the 35 same parts showing the switch blade in closed and open positions respectively,

Fig. 6 is a perspective of the actuating cam,

Fig. 7 is a detail of the actuating shaft,

Figs. 8 and 9 are perspective views of the supporting frame and spring and the switch blade respectively.

In Figs. 1 and 2 A represents a base block 45 of insulating material such as porcelain or rubber in which the switch elements are carried. At B is shown the usual threaded shell for the reception of the threaded base 50 of a lamp or other device. Fastened centrally to the block A and within the shell B is the usual spring center contact finger 1 for engagement with the usual central terminal of the lamp or plug. As shown this contact is made fast to the block A by means of 55 a screw 2 passing therethrough, and threaded

in a nut 3 seated in a depression 4 in the block A. Contact 1 has an extension arm 5 passing through a wall of the block A and terminating in a curved switch contact 6. The shell B is in electrical connection with a 60 binding post 7 near one edge face of the block by means of a metal yoke 8 which is made fast by the rivets 9 and 10 to the block A and holds the shell B fixed thereto. Opposite the contact 6 is placed a similar contact 11 formed as an extension of the binding post 12. The rear face of the block A is recessed at 13 to contain the moving switch parts which are carried by a sheet metal frame 14. As shown more particularly in 70 Figs. 3 and 8, this frame comprises a substantially U shaped portion having spaced sides 15 and 16 connected by a narrower portion 17. The portion 15 is provided with a leaf spring extension 18 which is notched 75 at 19 and 20 near its free end. The portion 16 has a central open slot 21 and the portion 15 has a long slot 22 terminating opposite the slot 21 in a portion of narrow width at 23. At 24 is shown a switch-blade 80 having a central rectangular slot 25 and at one end spaced ears 26 and 27. The slot 25 is of sufficient width to take over the portion 17 of the frame 14, while the ears 26 and 27 are spaced to fit the notches 19 and 20. 85 Member 24 is also of a width to fit snugly between the contacts 6 and 11. At 28 is shown a shaft carrying at 29 the usual switch actuating button. As shown in Fig. 7 the inner end of shaft 28 is circumferentially 90 grooved at 30 and 31, the grooved portions being of proper diameter to find bearing in the slot 21 and the narrow slot portion 23 of frame 14. The wide portion of slot 22 allows the shaft 28 to pass therethrough in 95 order to facilitate assembly of the parts. Between the grooves 30 and 31, shaft 28 has formed thereon as by striking up therefrom a pair of lugs 32 and 33. At 34 is shown an actuating cam block having a central perforation to fit the shaft 28, this cam being of a 100 length to fit easily between the spaced sides 15 and 16 of the frame 14. This block has a slot 35 within which the lugs 32 and 33 may extend and by which it is fixed to rotate with shaft 28. This cam is formed as a double wedge the faces thereof being at right angles to each other and tapering in opposite directions axially of shaft 28.

When assembled as shown in Fig. 3 the 110

cam block is held between the sides 15 and 16 of the frame and within the slot 25 of the switch blade 24, the end edge of the slot being pressed against the cam by means 5 of the spring extension 18 which thus resiliently holds the shaft 28 within the bearing slots 21 and 23. These parts as assembled are then placed within the recess 13 of the block A and held therein by means of 10 the head 36 of a screw. It should be understood that the switch blade 24 is of conducting material such as brass or the like but the button 29 is of insulating material in the usual manner.

15 The operation of the device is as follows: The leading in wires are connected to the binding screws 7 and 12, current leading directly from the screw 7 to the shell B in the usual manner. When the switch is closed 20 the switch blade 24 is in the position shown in Figs. 1 and 2 bridging the contacts 11 and 6, by which means the binding screw 12 is in electrical connection with the central spring contact 1 in the usual manner.

25 If now the button 29 be turned in either direction from the position shown in Fig. 1, one edge of the cam block 34 will impinge on the end of the slot 25 and push the blade 24 longitudinally against the pressure 30 of the spring portion 18 thus placing the spring under increased tension. At a certain point in the turning the angle of the edge of the block 34 as presented to the edge of the slot changes from the wedged taper in one direction to the wedged taper in the other direction. When the switch is closed the taper is away from the button 29 as shown as Fig. 4. On giving the button 35 29 a quarter turn, however, the wedge taper is in the opposite direction as shown in Fig. 5. As this mid position is reached the tension of the spring 18 urging the blade 24 against the cam block causes the blade to ride up the inclined wedge face, completing the quarter turn of the shaft 28, and throwing the blade 24 about its engagement with the spring 18 as a pivot out of bridging contact with the elements 6 and 11 and opening the circuit. The wider portions 40 of the frame end 15 engage either side of the slot 25 to limit the extent of movement of the contact blade in this direction. On turning the button 29 another quarter turn a similar action takes place to reverse 45 the direction of taper of the block 34 which is presented against the end of the slot 25, which action in a similar manner, snaps the switch blade 24 into bridging contact with the members 6 and 11 and closes the circuit, the wider portions of the frame 16 engaging the opposite side of the blade 24 either side of slot 25 limiting the extent of its motion in that direction.

From the above it is seen that this construction provides a simple snap switch

mechanism most of the parts being bent or formed from sheet materials and in which a spring element serves to hold the moving parts in assembled relation and also to move the switch blade alternately to open and closed position by identically the same motion of the spring.

Having thus described one embodiment of this invention, though it is evident that many changes might be made therein without departing from its spirit or scope what is claimed is:

1. A snap switch comprising a rotary shaft, a double wedge cam rotatable about its axis by said shaft, stationary switch contacts, a switch blade to cooperate therewith, and yieldable means arranged to longitudinally force said blade against said cam transversely thereof whereby it is caused to move into or out of engagement with said contacts upon each quarter turn of said shaft.

2. A snap switch comprising a rotary shaft, a cam driven thereby and having quadrants thereof sloping in alternate directions to its axis, stationary contacts, a switch blade to cooperate therewith, and yieldable means arranged to force said blade transversely against the said cam whereby it is caused to move into and out of engagement with said contacts by the rotation of said cam.

3. A snap switch comprising a rotary shaft, a double wedge cam driven thereby, stationary contacts, a movably pivoted switch blade to cooperate with said contacts, and spring means to force said blade against said cam transversely thereof whereby it is caused to oscillate into and out of engagement with said contacts as the cam is rotated to present different wedge faces thereto.

4. A snap switch comprising a rotary shaft, a double wedge cam driven thereby, stationary contacts, a switch blade to cooperate with said contacts, a movable fulcrum for said switch blade, and spring means acting through said fulcrum to force said switch blade against the wedge surfaces of said cam transversely of its axis.

5. A snap switch comprising a rotary shaft, a double wedge cam driven thereby, stationary contacts, a switch blade to cooperate with said contacts, a leaf spring having its free end adapted to pivotally engage said switch blade and force it against the wedge surface of said cam transversely of its axis.

6. A snap switch comprising a slotted switch blade, a spring pressed fulcrum for said blade, and a rotary cam having faces alternately inclined to its axis and transversely engaging the blade within the slot thereof.

7. A snap switch comprising a frame

- member having spaced portions, a spring actuated fulcrum carried by one of said portions, a switch blade having a slot to receive said frame and pivoted on said fulcrum, a shaft journalled in said frame, a cam actuated by said shaft and engaging said blade within the slot thereof, and stationary switch contacts arranged to cooperate with the free end of said blade. 5
- 10 8. A snap switch comprising a frame member having spaced portions, one of said portions having a spring extension, a switch blade having a slot to receive said frame and pivoted on the free end of said spring extension, a shaft journalled in said frame, and a cam fixed to said shaft and engaging within the slot of said blade, said cam being actuatable on the turning of said shaft to swing said blade alternately in opposite directions. 20
9. A snap switch comprising a frame member having spaced end portions joined by an intermediate reduced portion with shoulders at the ends thereof, a spring actuated fulcrum carried by one of said end portions, a switch blade having a slot to receive the reduced portion of said frame and pivoted on said fulcrum, a shaft journalled in said frame, a cam actuated by said shaft and engaging said blade within the slot thereof, and stationary switch contacts arranged to cooperate with the free end of said blade. 25
- 15 In testimony whereof he affixes his signature.

ARTHUR W. CLAUDER.
